US0D1063456S

(12) **United States Design Patent** (10) **Patent No.:** **US D1,063,456 S**
(45) **Date of Patent:** **** Feb. 25, 2025**

(54) **STORAGE UNIT**

(71) Applicant: **Bin Liao**, Zhuhai (CN)

(72) Inventor: **Bin Liao**, Zhuhai (CN)

(**) Term: **15 Years**

(21) Appl. No.: **29/965,304**

(22) Filed: **Sep. 26, 2024**

(51) LOC (15) Cl. **06-04**

(52) U.S. Cl.

USPC **D6/560**; D6/662

(58) **Field of Classification Search**

USPC D6/671.1, 661, 657, 671, 663, 660, 559,
D6/561, 662.1, 662, 671.2, 560

CPC A47B 55/00; A47B 67/04; A47B 83/001;
A47B 83/045; A47B 97/00; A47B 81/00;

(57) **CLAIM**

The ornamental design for a storage unit, as shown and described.

DESCRIPTION

FIG. 1 is a top perspective view of a storage unit, showing my new design;

FIG. 2 is a bottom perspective view thereof;

FIG. 3 is a front perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view showing the locker in an open state; and,

FIG. 11 is an enlarged detail view of area 11 in FIG. 2. The broken lines in the drawings illustrate the portions of the storage unit, which form no part of the claimed design. The dash-dot-dash broken lines encircling the enlarged views are for annotative purposes only and form no part of the claim thereof.

1 Claim, 11 Drawing Sheets
